(57) **CLAIM**

The ornamental design for a housing for a communication interface adapter or similar articles, as shown and described.

DESCRIPTION

FIG. 1 is a bottom, side and front perspective view of an ornamental design of a housing for a communication interface adapter or similar articles showing our new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken line areas form no part of the claimed design.

1 Claim, 4 Drawing Sheets

FIG. 1

FIG. 2

FIG. 3

FIG. 4

FIG. 5

FIG. 6

FIG. 7
